enstein

Application February 23, 1933, Serial No. 658,048
In Germany January 19, 1933

1 Claim. (Cl. 22—68)

This invention relates to a machine for casting under pressure with press chamber not heated or feebly heated, from which the material to be pressed is forced by a piston into a permanent 5 mould, preferably of steel.

The machines for casting under pressure of this type, which are especially employed for working metals possessing a high melting point, the liquid or pasty metal to be pressed must, on account of 10 the strong cooling effect of the moulds, be filled into the press chamber only directly before the shot, and after the shot the residue from pressing which has remained in the press chamber and solidified in the meantime must be completely 15 removed from the press chamber. The press chamber must therefore be so arranged that it can be opened or rendered accessible at every operation for filling and for removing the residue from pressing.

20 Machines for casting under pressure of this type have been carried out already, in which the press chamber is partly arranged in the aggregate containing the mould and partly carried out as an independent part separate of the casting mould.

25 In the constructions of the first mentioned kind the press chamber in the mould half is accommodated as a cavity open towards the separating gap so that by the closing of the mould this 30 chamber is closed by the other half of the mould and liberated by the opening of the mould. These constructions prevent the inconveniences that the mould can be closed only after the charging of the press chamber (so that the metal which has 35 been filled in is exposed to cooling by the walls for a comparatively long time), and that the forces exerted by the press plunger (especially also the considerable shocks in the mass occurring at the end of the stroke) are transmitted 40 directly upon the movable mould half, so that they have the tendency to cause bursting of the mould.

These inconveniences are avoided in those constructions, in which the press chamber is carried 45 out as a separate part, closed in itself, which is connected with the mould (situated either at the side or above or below the press chamber) only by a channel (the ingate aperture). In all such constructions the press chamber must have a re- 50 leasable closure, which during the charging of the mould remains in the closing position and inter- 55 rupts the pressures exerted by the press plunger but is opened after the termination of the pressing stroke so that it admits of the removing of solidified metal residue and of the recharging of the press chamber.

This shutting off means is formed in machines as for instance according to the American Patent 1,555,284 by a (rotary or slide) valve which is 60 movable in a direction perpendicular to the course

of the piston. All these constructions possess the inconvenience that the sliding and packing faces, of the perfect condition of which the usefulness for service depends, are exposed to direct contact with the metal to be pressed and therefore are subjected to extremely unfavorable thermal and mechanical stresses so that they soon become damaged.

A further inconvenience of this manner of construction consists in that the closure must bear 10 absolutely tightly upon the seating surface of the press chamber as otherwise, if even the tiniest gap remains open, metal would without fail penetrate through the same under the action of the high pressing pressure and the burr formed thereby 15 would prevent the correct working of the slide. An absolutely tight closing of the press chamber has, however, the result that all the air in the press chamber will be forced by the forward moving piston into the mould and be dammed up 20 therein, whereby the enclosing of air in the casting material will be favored.

In the machine according to the German Patent 539,817 an axially shiftable plunger serves for shutting off the pressure chamber; which piston 25 in the charging position of the machine covers the ingate channel leading to the casting mould, is forced back at the beginning of the pressure stroke by the press plunger until the ingate channel is liberated, then during the period of mould 30 charging immovably held by an abutment (shiftable perpendicularly to the cylinder axis) and then moved completely out of the press chamber 35 at the termination of the pressing stroke after withdrawing of the abutment.

This arrangement possesses, in comparison with the above mentioned arrangements, the advantage that the sliding and seating surfaces of the shutting off piston do not come into touch with the metal to be pressed. However, the shutting off piston, which in this construction serves 40 at the same time for controlling the ingate channel, must assume successively, during the working operation, three different, determined positions. This necessitates on the one hand a certain complicating of the actuating means, and on the other hand does not allow of employing other but cylindrical (particularly conical) seating surfaces, which in many instances are very 45 desirable.

The present invention differs from what is known in that the closing of the charging—or ejecting aperture of the press chamber is effected by an element which is at standstill during the whole pressing stroke, the seating surface of which is shaped rotation-symmetrically relative to the axis of the press chamber (preferably as cylindrical or conical wall) and the removing of which during the opening of the press chamber takes place in axial direction (or, in other but 55 60 65 70 75 80 85 90 95 100 105 110 115 120 125 130 135 140 145 150 155 160 165 170 175 180 185 190 195 200 205 210 straight movement, on a track with axial initial direction).

Several embodiments of the invention are illustrated by way of example in the accompanying drawings:

Figs. 1 and 2 show the diagram of a machine for casting under pressure with conical closure in two working positions.

Figs. 3 and 4 diagrams of two other possible forms of construction with cylindrical seating surface and plane circular ring seating surface during the recharging of the mould.

In all figures designates: A the cylindrical press chamber, B the press plunger, C the press chamber closure, D the charging scoop for charging the press chamber, E the connecting channel between press chamber and hollow mould, F the immovable mould half, G the movable mould half, H the hollow mould, J the ejecting device.

From the drawings can be clearly seen in which manner the cycle of a machine carried out according to the invention takes place. After the mould has been closed, the press plunger B is brought into its initial position and metal is charged into the press chamber from above, the metal being taken by means of a scoop or ladle D from a melting vessel separate from the machine (not indicated in the figures) (Fig. 1). The closing piece is then brought into the closing position, in which it is securely held as upper closure of the press chamber during the whole period of the pressing stroke (Figs. 2 to 4). The press plunger is then moved upwards, the metal being forced into the mould. The closure C is then opened again, whereupon the residue from pressing can be removed from the press chamber and—after the opening of the mould—the casting from the latter.

The examples illustrate the advantages of the constructions carried out according to the invention. The press chamber closure, which in any case is particularly strongly stressed thermally and mechanically, is, owing to the rotation-symmetrical shape of the seating surface, very easy to produce in workshop technical respect. The seating surfaces are protected against the direct action of the metal to be pressed. By conical or spherical shape of the seating surfaces it can be obtained that a metal burr penetrating into the packing joint cannot give cause for the seizing of the closure.

As regards construction machines according to the invention can be carried out in very various manners. For example the seating surface of the press chamber closure can be cylindrical (Fig. 3), conical (Figs. 1, 2), spherical or even planar (Fig. 4). The opening and closing movement of the closure piece C can (if the seating surface is conical (spherical or plane) be either a straight line movement (Fig. 3) or a folding movement (Figs. 1, 2) or a combined movement. The controlling and actuating of this movement can be effected by control means and power means of most different kind. Either such control means can be employed, which as for instance elbow levers or eccentrics lock themselves the closure piece in the mould closing position by their dead centre (Figs. 1, 2), or the movement of the closure piece C can be controlled by any element not locking the closing position (such as for instance lever, tooth drive or others) and the closure piece can be locked (Fig. 3) in the closing position by any separate locking element (such as for instance a latch or bolt or others). The

closure piece C may further be securely held in the closing position by the power means actuating its movement. When actuated by a hydraulic cylinder, the closure piece can be locked in the closing position in especially simple manner in that the cylinder side actuating the closing movement is shut off from the conduit for water under pressure, as in this case the enclosed quantity of water owing to its incompressibility presents yielding of the hydraulic piston and thereby of the closure piece.

The whole arrangement, serving for guiding and actuating the closure element, may further be arranged in such a manner on the machine frame, that during the opening it can be slewed away from the press chamber so that the closure piece C need carry out only a very short stroke and the press chamber is quite freely accessible in the open position.

The ingate channel E leading to the mould can either interrupt the wall of the press chamber or be arranged at the end of the press chamber as a gutter extending transversely across the seating surface. The first mentioned arrangement is always advisable if the ingate channel A extends through the one mould half (Figs. 1 to 3). In this instance the residue from pressing must be shorn off by the ingate pin after the complete filling of the mould in order that it may be ejected from the press chamber and that the ingate pin together with the casting can be removed from the front mould plate during the opening of the mould. In this case the casting together with the ingate metal and the residue from pressing is completely liberated by removing the closure piece C and opening of the mould so that all these parts together can be ejected.

Evidently the possibilities of carrying out the invention are not limited to those indicated in the above specification and illustrated in the drawings. Machines for casting under pressure according to the invention may be constructed in many other manners, as the essential feature of the invention consists in that the closing of the press chamber is effected by a closure piece with preferably rotation-symmetrical seating surfaces, which closure piece during the whole pressing stroke stands immovably in the closing position but after the termination of the recharging of the mould is transferred from this closing position into an opening position liberating the press chamber and by a movement the direction of which coincides at least at the beginning with the direction of the press chamber axis.

We claim:—

A machine for casting metals under pressure, comprising an independent press chamber having at one end a detachable closure piece, a casting mould separate from the press chamber and its closure piece, a piston for supplying the material to be pressed to the casting mould under pressure from the press chamber, said closure piece being stationary during the pressure stroke, means for opening and closing the press chamber by movement of the closure piece, the direction of said movement adjacent the closing position approximately coinciding with the direction of the press chamber axis and means whereby the closure piece follows a swinging movement about an axis at right angles to the axis of the chamber.
